UNITED STATES PATENT OFFICE.

MARSHMAN W. HAZEN AND OTTO PETERMANN, OF NEW YORK, N. Y., ASSIGNEES, BY
MESNE ASSIGNMENTS, TO CORONA TYPEWRITER COMPANY, INCORPORATED, A
CORPORATION OF NEW YORK.
PAPER-FEED.

1,130,510.

Specification of Letters Patent. Patented Mar. 2, 1915.

Original application filed March 27, 1909, Serial No. 486,181. Divided and this application filed June 7, 1909, Serial No. 500,696. Renewed August 10, 1912. Serial No. 714,472.

To all whom it may concern:

Be it known that we, MARSHMAN W. HAZEN and OTTO PETERMANN, citizens of the United States and of the Republic of Switzerland, respectively, and residents of New York, county and State of New York, have invented certain new and useful Improvements in Paper-Feeds, of which the following is a full, clear, and exact description.

10 This invention relates more particularly to paper feeding means for typewriting machines, and is a division of our pending application Sr. No. 486,181, filed March 27th, 1909, Patent 1,094,560.

15 The primary object of the invention is to provide simple and efficient means mounted upon a carriage for feeding the paper to a stationary platen located adjacent thereto.

20 A further object of the invention is to provide simple means whereby a part of the feeding means may also be employed as a platen.

25 With these and other objects in view, the invention will be hereinafter more particularly described with reference to the accompanying drawings, which form a part of this specification, and will then be pointed out in the claims at the end of the description.

30 In the drawings, Figure 1 is a longitudinal section, partly in elevation, of a machine showing one form of feeding means embodying our invention; and Fig. 2 is a detail side elevation of one member of the carriage in which the feeding means is mounted.

35 The machine frame 10 may be of any desired construction and supported within the same are a plurality of brackets 11 to each of 40 which are pivoted a plurality of key levers 12. These key levers are connected to operate the type-bars 13, and said type-bars are provided with type-heads having one or more characters thereon, which, in their 45 movement, engage the surface of a platen 14.

Instead of the type striking the usual 50 cylindrical platen, the type may engage a flat surface, as 15, formed as a part of the plate-like platen 14, which extends transversely of the machine and is movable with the carriage 16, the said carriage having two frame members 17 and 18 to the former of which the plate or platen 14 is secured. The platen 14 may be curved for a greater part

of its width except at the straight part 15, 55 forming the printing surfaces, and said platen may be secured to the part 19 of the carriage frame member 17 or otherwise held as desired in a position so that the paper or work may be readily passed about 60 the same, though instead of the type striking directly against a metal surface, a yielding surface or strip 20 may be provided, which strip may be so attached that it may be readily replaced in case of wear. 65

A roll 21 corresponding to the usual platen roll may be journaled in the frame member 17 of the carriage 16, and may be provided with the usual finger pieces 22 by which the roll may be rotated, the said 70 finger pieces 22 being secured to the shaft of the roll 21, and to permit the roll and platen frame to move vertically the carriage frame member 18 is slotted where the shaft passes through said member. At the rear of the 75 roll 21 is a second smaller roll 23, which normally engages the roll 21, and at the front of said roll 21 is a still smaller roll 24. The shaft 25 of the roll 23 is held in slots 26 in the frame member 17 and has peripheral grooves at the ends thereof, and held to the ends of the shaft in such a way as to permit the shaft to rotate are the springs 27 which have one end connected to levers 28. These levers 28, Fig. 2, are pivoted at 29, and have their inner ends, as 30, adapted to be engaged by screws 31, so that the tension of the springs 27 may be varied and the roll 23 yieldingly held 80 against the larger feed roll 21. The roll 24 is similarly held to the roll 23, and has the ends of its shaft 32 held to slide and rotate in the slots 33 of the carriage frame member 17, and connected to said shaft are the springs 34 which are connected to the 95 levers 35, the latter being pivoted at 36 and normally forced in one direction by screws 37 to vary the tension of said springs. It will be seen that the roll 21 may be used as a 100 platen by having the type engage the surface thereof instead of the plate 14, in which case the latter may be dispensed with.

While we show and describe certain features of the machine other than the feeding means, we do not claim herein such features 105 as they form part of our pending application hereinbefore referred to or of other divisional and co-pending applications.

From the foregoing, it will be seen that simple feeding means for the paper is provided which is adapted to feed the paper about a stationary platen located adjacent thereto; and that simple means is provided for yieldingly holding the parts of the feeding means to properly engage the work or paper.

Having thus described our invention, we 10 claim as new and desire to secure by Letters Patent:—

1. In a typewriting machine, the combination with a carriage, of a platen mounted to move with the carriage, a large feed 15 roll, two smaller rolls adapted to engage the larger roll about which latter the work sheet is adapted to pass to be fed about the platen when the larger roll is rotated, pivotally held levers, springs connecting the 20 levers to the smaller rolls, and means for varying the tension of said springs.

2. In a typewriting machine, the combination with a carriage, of a platen mounted to move with the carriage, a large feed roll, 25 two smaller rolls adapted to engage the larger roll about which latter the work sheet is adapted to pass to be fed about the platen when the larger roll is rotated, pivotally held levers, springs connecting the levers 30 to the smaller rolls, and screws for varying the tension of said springs.

3. In a typewriting machine, the combination with a carriage, of a large roll mounted on the carriage, two smaller feed 35 rolls adapted to engage the larger roll to feed the work sheet, pivotally held levers arranged on the outside of the carriage, springs connecting the levers to the smaller rolls, and means for varying the tension of 40 the springs.

4. In a typewriting machine, the combination with a carriage, of a large roll mounted on the carriage, two smaller feed rolls adapted to engage the larger roll to feed 45 the work sheet, pivotally held levers arranged on the outside of the carriage, springs connecting the levers to the smaller rolls, and screws engaging the levers for varying the tension of said springs.

5. In a typewriting machine, the combi-

nation of a carriage, a large roll, two smaller rolls adapted to engage the larger roll between which latter and the two smaller rolls the work is adapted to pass to be fed when the larger roll is rotated, and 55 levers located on the outside of the ends of the carriage and yieldingly connected to the smaller rolls to yieldingly hold the smaller rolls against the large roll.

6. In a typewriting machine, the combination of a carriage, a large roll and two smaller rolls adapted to engage the larger roll between which latter and the two smaller rolls the work is adapted to pass, and springs located on the outside of the 65 ends of the carriage connected to the shafts of the smaller rolls.

7. In a typewriter, the combination of a carriage having two frame members, a platen mounted in one of the frame members, a large roll, two smaller rolls adapted to engage the larger roll between which the work is adapted to pass, the shafts of said rolls projecting through one of said frame members, levers pivotally held to the frame 75 member in which the large roll is mounted on the outside thereof, springs connecting the levers to the shafts of the small rolls, and screws engaging a part of the levers to vary the tension of the springs. 80

8. In a typewriter, the combination of a carriage having two frame members, a platen mounted in one of the frame members, a large roll, two smaller rolls adapted to engage the larger roll between which 85 latter and the two smaller rolls the work is adapted to pass, levers pivotally held to the frame member and located on the outside ends thereof in which frame member the large roll is mounted, springs connecting the 90 levers to the shafts of the small roll, and means to vary the tension of the springs.

This specification signed and witnessed this 4th day of June, A. D. 1909.

MARSHMAN W. HAZEN.
OTTO PETERMANN.
